UNITED STATES PATENT OFFICE.

CLARENCE EDWIN BAGFORD, OF CORWIN, OHIO.

BARREL-ROLLER.

No. 800,199.

Specification of Letters Patent.

Patented Sept. 26, 1905.

Application filed February 27, 1905. Serial No. 247,502.

To all whom it may concern:

Be it known that I, CLARENCE EDWIN BAGFORD, a citizen of the United States, residing at Corwin, in the county of Warren and State 5 of Ohio, have invented a new and useful Barrel-Roller, of which the following is a specification.

This invention relates to means for rolling barrels, and has for its object to provide a 10 simple and improved device of this character capable of being conveniently manipulated by hand for engagement with a barrel to roll the latter upon a floor or other support, so as to shift the barrel from one place to another 15 without lifting the same from the floor.

Another object of the invention is to have the device adjustable, so as to fit barrels of different lengths and to facilitate the application 20 of the device to the barrels without preparation of the latter beyond laying them down on their sides.

With these and other objects in view the present invention consists in the combination and arrangement of parts, as will be herein- 25 after more fully described, shown in the accompanying drawings, and particularly pointed out in the appended claims, it being understood that changes in the form, proportion, size, and minor details may be made within 30 the scope of the claims without departing from the spirit or sacrificing any of the advantages of the invention.

In the accompanying drawings, Figure 1 is a perspective view of a barrel-rolling device 35 embodying the features of the present invention. Fig. 2 is an end elevation of the device, showing the application thereof with a barrel indicated in dotted lines.

Like characters of reference designate cor- 40 responding parts in both figures of the drawings.

The device of the present invention includes spaced head-frames, (designated in general 1 and 2,) each head member consisting of di- 45 verged side bars 3 and 4, which are connected at their diverged ends by means of a bowed or arched cross-bar 5, constituting a handle. The sides 3 and 4 and the handle 5 are prefer- 50 ably formed from a single metallic bar bent into an approximately V shape, with the sides 3 and 4 diverged from the handle. At the outer end of each side of each head-frame there is a roller or wheel 6, preferably in the nature of a disk, which is applied to the outer 55 face of the head member and journaled upon a bolt 7, there being a guard bar or strap 8

applied diametrically at the outer face of the roller and pierced by the bolt 7, the inner end portion of the guard being laterally offset, as at 9, to form an attaching-shank, which is 60 rigidly connected to the adjacent head by means of a bolt 10, whereby the wheel works between the guard 8 and the adjacent side or leg of the head, so as to prevent wabbling of the wheel or roller. The corresponding legs 65 of the head members are connected by the bars 11 and 12, which are longitudinally overlapped and are provided with terminal lateral extensions or brackets 13 and 14, respectively, which are applied to the inner faces of the 70 respective heads and rigidly secured thereto by means of the bolts 7 and 10. One of these connecting-bars is provided with a longitudi- 75 nal slot 15, and the other bar carries a pair of screws or threaded projections 16, which work in the slot 15, with wing-nuts 17 applied to the projected ends of the screws and adapted to be set against the slotted bar, so as to rigidly and adjustably connect the bars, whereby the head members of the device are also rigidly and adjustably connected.

In using the device, as indicated in Fig. 2 of the drawings, the operator grasps one of the handles 5 in each hand and places the rollers 6 against the side of the barrel, which has 85 been indicated in dotted lines in Fig. 2, and by pushing upon the handles the barrel will be rolled over and over upon the floor or other support, the rollers 6 of course rotating under the influence of the rotating barrel, and 90 thereby operating as antifriction devices to permit of a free rolling of the barrel. In changing to barrels of different lengths the head members 1 and 2 are separated or drawn together to accommodate the device to barrels of any length within the capacity of the 95 device.

From the foregoing description it will be understood that the device of the present invention is entirely complete in itself and may 100 be conveniently applied to barrels without any preparation of the latter and without lifting the barrel to place the same upon the device, wherefore the rolling of the barrel by means of the present device may be effected 105 in a very simple and convenient manner without the expenditure of much energy.

Having thus described the invention, what is claimed is—

1. A barrel-rolling device comprising spaced 110 heads capable of adjustment toward and away from one another, each head having a pair of

spaced barrel-engaging antifriction-rollers at one end and a handle at the opposite end, the handles of the heads being independent of one another, and means connecting the heads and 5 adjustable to vary the space between said heads.

2. A barrel-rolling device comprising spaced heads having diverged sides, rollers mounted upon the diverged ends of the sides, handles 10 connecting the other ends of the sides, the handle of one head being independent of the handle of the other head, pairs of bars carried by the roller ends of the sides and overlapped between the heads, one member of each pair 15 of bars having a longitudinal slot, a threaded projection carried by the other bar and working in the slot, and a clamping-nut carried by the projection to adjustably connect the bars.

3. A barrel-rolling device comprising spaced 20 heads having diverged sides, rollers carried

by the outer faces of the diverged terminals of the sides, handles connecting the other ends of the sides, endwise-adjustable overlapped bars having terminal lateral extensions applied to the inner faces of the corresponding 25 sides of the heads, guards applied to the outer sides of the heads and overlapping the respective rollers, bolts piercing the extensions of the bars, the heads, the rollers, and the guards and constituting axes for the rollers, and other 30 bolts piercing the extensions of the bars, the heads and the guards at the sides of the rollers.

In testimony that I claim the foregoing as my own I have hereto affixed my signature in the presence of two witnesses.

CLARENCE EDWIN BAGFORD.
